ATTORNEY

UNITED STATES PATENT OFFICE.

BOYCE D. PONTON, OF HALLETTSVILLE, TEXAS.

PIPE-CLAMP.

1,274,774.

Specification of Letters Patent.

Patented Aug. 6, 1918.

Application filed July 28, 1916. Serial No. 111,867.

To all whom it may concern:

Be it known that I, BOYCE D. PONTON, a citizen of the United States, residing at Hallettsville, in the county of Lavaca and State 5 of Texas, have invented certain new and useful Improvements in Pipe-Clamps, of which the following is a specification.

My invention relates to vises, and more, particularly to an improved gripping means 10 therefor.

The principal object of the invention may be said to reside in the provision of a pair of auxiliary gripping jaws, or vises, which may be readily engaged with the oppositely 15 moving jaws of the conventional form of vise, and may be quickly removed therefrom, in order that the auxiliary jaws of different size may be substituted therefor, thus providing for means whereby a section 20 of piping or other material may be quickly and securely clamped within the vise.

The invention has more especial reference to the novel manner in which the auxiliary jaws are arranged, the same being engaged 25 with an expansible spring element, whereby, they will at all times, be held in contact with the jaw faces of the vise, consequently preventing the displacement of the former when the device is loosened or disengaged from the material as previously held 30 thereby.

Another important characteristic of the invention, resides in the provision of abutment fingers, which are removably received 35 by the auxiliary jaws, whereby the same may be maintained in proper position, with respect to the said vise jaws.

The annexed drawings and following description sets forth in detail, certain construction embodying the invention, such disclosed means, constituting however, but one 40 of the various mechanical forms in which the principle of the invention may be used.

In said annexed drawings:—

45 Figure 1 is a side elevation of my improved auxiliary clamping or gripping jaws,

Fig. 2 is a fragmental end elevation of one of the jaws, showing a portion of the 50 same in plan section,

Fig. 3 is a transverse section taken on the line 3—3 of Fig. 1,

Fig. 4 is a fragmentary vertical section taken on the line 4—4 of Fig. 2, and

55 Fig. 5 is an enlarged perspective view of

one of the jaws, illustrating the relative position of the abutment fingers.

Referring now more specifically to the drawings, wherein like reference numerals indicate corresponding parts throughout the 60 several views, I provide a pair of gripping or clamping jaws, indicating the same by the numerals 1 and 2. To the opposite side faces of these jaws, I affix the strips 3 and 4, by rivets or the like, as at 3', the lower 65 ends of which extend beyond the adjacent end portions of the jaws 1 and 2. The said extended ends of the strips 3 and 4 are provided with suitable openings, the purpose of which will be hereinafter apparent. The 70 gripping jaws 1 and 2 are provided with the usual concaved portions upon their adjacent faces which are serrated as at 5 and 5', whereby a section of piping or other material may be securely held therebetween. 75

Longitudinally extending recesses or pockets 6 are formed within the opposite sides of the jaws 1 and 2 and have leaf springs 7 arranged therein, which springs are secured to the said jaws by means of set-screws 8. 80 In the lower portions of the said jaws 1 and 2, I arrange a set of pockets 9, these pockets extending transversely of their said respective jaws and have arranged therein leaf springs 10 similar to the springs 7, the same 85 being secured in position by means of set-screws 11 which are embedded within their respective jaws. These longitudinally and transversely arranged pockets are adapted to receive abutment fingers which comprise 90 strips of spring metal of substantially U-shape as at 12, one end of which is bent at right angles thereto, as at 13, this providing for the so-called abutment finger. By providing these abutment fingers, it will be evident that the positioning of the auxiliary jaws 1 and 2 with relation to the jaws of the particular device to which they are applied will be greatly facilitated, the said 95 finger serving as means for maintaining the jaws in proper position. Thus, when the abutment fingers are inserted within the longitudinally extending pockets 6, it being noted that these pockets are of less width than the transversely extending pockets 9, 105 one leg portion of the U-shaped element is received thereby and is engaged by the springs 7 which are arranged within the said pockets, consequently holding the fingers in position and preventing the acci-

100
105
110

dental outward movement thereof. The abutment fingers are inserted within the transversely arranged pockets 9, the entire U-shaped element 12 is received thereby and retained therein by means of the leaf spring 10 which engages the one side portion thereof.

In order to provide for means whereby the auxiliary jaws 1 and 2 will be normally held in engagement with the jaws of the vise to which they are attached, I secure to the extended portions of the strips 3 and 4, the ends of a circular expansible spring 14, by means of bolts 15 which are passed through the openings arranged within the end of said extension. It will also be noted, that the bolts 15 will permit the expansible spring 14 to be swung to one side, should the same be in the way when removing or inserting a pipe within the vise.

When using my improved clamp jaws for a section of pipe or the like in a horizontal position within the vise, the abutment fingers 13 are engaged with their pockets 6 as arranged within the upper ends of the jaws 1 and 2. The jaws are then inserted between the vise jaws and as will be obvious, the expansible springs 14, as connected therewith, will cause the same to be spread and engaged with the said vise jaws, thus preventing accidental displacement thereof. The abutment fingers 13 will engage the adjacent side portions of the vise jaws, not shown, and consequently will maintain the said auxiliary jaws 1 and 2 in proper position with respect to the former. With the attachment thus in position, the vise may be then tightened, to clamp the material as arranged between the auxiliary jaws 1 and 2, therein. Should the user desire to clamp a piece of material within a vise and have the same arranged vertically, the abutment fingers 13 are then engaged with the transversely disposed pockets 9. Thus, when the auxiliary jaws 1 and 2 are placed between the vise jaws, the said fingers will engage the adjacent side portions of said vise jaws, and consequently, cause the auxiliary jaws to be properly received thereby and maintain the same in proper position at all times. As above stated, should the springs 14 interfere with the inserting or removing of a piece of material within the vise, the same may be swung at substantially right angles to the strips 3 and 4, the bolts 15 serving as the necessary pivot points.

It is to be understood, that the jaws 1 and 2, if so desired, may be detachably secured to the strips 3 and 4, thus enabling the user to readily remove the same therefrom, and to substitute jaws of different size and configuration therefor. However, if so desired, the jaws may be fixedly secured to

their respective strips 3 and 4, and when it is desired to remove the same in order that 65 jaws of different size may be substituted, the bolts 15 will be removed and then replaced when the desired jaws are in position.

Other modes of applying the principle of my invention may be employed instead of 70 the one explained, change being made as regards the construction therein disclosed, provided the means stated by any of the following claims or the equivalent of said 75 stated means be employed.

I therefore claim as my invention:

1. An attachment for vises comprising a pair of auxiliary jaws, said jaws having pockets formed therein, abutment fingers comprising U-shaped elements having outwardly extending projections formed thereon, said U-shaped elements extending into said pockets, whereby said auxiliary jaws will support said abutment fingers, and said abutment fingers projecting beyond said 85 jaws.

2. An attachment for vises comprising a pair of auxiliary jaws, said jaws having pockets formed therein, springs carried upon said pockets, and abutment fingers comprising U-shaped elements having projections extending outwardly therefrom, said U-shaped elements projecting into said pockets, whereby said spring will hold said elements against displacement, and said projections being adapted to support said jaws upon a support.

3. An attachment for vises comprising a pair of auxiliary jaws, said jaws having pockets formed therein, abutment fingers 100 comprising U-shaped elements having projections extending outwardly therefrom, said U-shaped elements removably fitting within said pockets, and flat springs secured adjacent to the inner end of said pockets 105 and projecting toward the outer end of said pocket so as to be in the path of movement of the U-shaped elements positioned within said pockets, thus firmly bearing upon said U-shaped elements for holding the same 110 against accidental displacement and said projections being adapted to support said jaws upon a support.

4. An attachment for vises comprising a pair of auxiliary jaws, a flat circular spring pivotally connected to said jaws, and supporting means carried by said jaws, and said flat spring being capable of being swung to one side to project at an angle to said auxiliary jaws.

In testimony whereof I affix my signature in presence of two witnesses.

BOYCE D. PONTON.
